UNITED STATES PATENT OFFICE.

VOTAW S. DURBIN, OF ST. LOUIS, MISSOURI.

AUTOMATIC TRAIN-PIPE COUPLING.

1,189,801.

Specification of Letters Patent.

Patented July 4, 1916.

Application filed March 1, 1915. Serial No. 11,149.

To all whom it may concern:

Be it known that I, VOTAW S. DURBIN, a citizen of the United States, residing in the city of St. Louis and State of Missouri, have invented new and useful Improvements in Automatic Train-Pipe Couplings, of which the following is a specification.

This invention relates to certain new and useful improvements in automatic train pipe couplings, and has for its general object to simplify the construction of an apparatus of this character, and at the same time to increase the efficiency thereof by insuring reliability in operation under all normal conditions of service.

The invention relates particularly to improvements in the form of train pipe coupling described and illustrated in my allowed application, No. 740,313, filed January 6, 1913, and has for its specific objects to provide an improved manner of supporting the coupling members; to provide an improved means for actuating the locking mechanism; to provide improved means for detachably securing the hose-pipe nipples on the coupling-heads; and to an improvement in the manner of mounting the coupling-heads on the plunger of the coupling so as to render them self-adjusting.

Other objects of the invention relate to details of construction and to combinations and operation of parts all of which will be more clearly understood from the detailed description following:

In the accompanying drawings,—Figure 1 is a view in side elevation showing my invention supported from the ordinary couplings of a car; Fig. 2 is a view, partly in plan and partly in horizontal section, showing two coupling-heads in coupled relation, the section being taken through one of the coupling-members and its plunger; Fig. 3 is a longitudinal sectional view of the parts shown in Fig. 2; Fig. 4 is a view in front elevation, or a face view, of one of the coupling-members; Fig. 5 is a view, partly in rear elevation and partly in section of the same; Fig. 6 is a fragmentary view in rear elevation on an enlarged scale showing one hose-pipe nipple in position on the rear face of the coupling-member and a second nipple removed, and also illustrating a securing means for preventing the locking-ring used in connecting the nipple to the coupling-member from working loose; Fig. 7 is a sectional view taken on the line 7—7 of

Fig. 6; Fig. 8 is a fragmentary, broken, sectional view taken substantially on the line 8—8 of Fig. 6, and showing in side elevation the locking-mechanism illustrated in Fig. 6; and Fig. 9 is a fragmentary, longitudinal, sectional view, on the same scale as Fig. 6, illustrating an improved automatic means for permitting the escape of condensed steam from the steam pipe system.

Referring now to these drawings, the numerals 1, 2, indicate, generally, two interlocked car-couplings, and the numerals 3, 4, two train pipe coupling-heads, each of which is adjustably mounted on a plunger 5, 6, respectively. As the coupling-heads 3, 4, and the parts connected thereto are identical in construction, a description of one will answer equally well for the other.

Referring particularly to Figs. 1 to 5, the numeral 7 indicates a bracket which is provided on opposite sides with a diagonally-disposed groove 8 in which are received and secured, as by bolts 9, arms 10 connected at their upper ends by a cross-bar 11. The arms 10 and cross-bar 11 are preferably formed integral. The cross-bars 11 are secured to the under sides of the car-couplings 1, 2, as illustrated in Fig. 1. Each bracket 7 is constructed to be secured by frame members (not shown) to the car body, in the manner indicated in my application aforesaid, such manner of mounting being used on passenger cars. Each of the coupling-heads 3, 4, has projecting from its front face, at one side of its center, a projection 12, and at its other side is provided with an opening 13 to receive a corresponding projection 12 on the opposite coupling-head.

An important feature of the present invention relates to the manner of securing the hose-pipe connectors, or nipples, in the coupling-heads. Each of the coupling-heads is provided with an apertured boss 14 in which is secured the nipple 15 of the signal-pipe; with an apertured boss 16 in which is secured the nipple 17 of the train-pipe; and with an apertured boss 18 in which is secured the nipple 19 of the steam-pipe. The manner of securing each of the nipples 15, 17 and 19 in place being substantially the same, I will describe the construction by which this is accomplished in connection with the apertured boss 18 and the nipple 19, illustrated in Figs. 7 to 9. Formed integral with the boss 18, and located on opposite sides thereof, respectively,

are two ears 20, each of which has a recess 21 providing a shoulder 22 extending parallel with the face of the boss 18. The nipple 19 is in the form of an "elbow," and 5 has its outer end portion 23 suitably shaped to receive and retain the end of a hose-pipe, in the usual manner, and its opposite end portion, 24, straight, for insertion in the aperture of the boss 18, and provided with an 10 annular shoulder 25 for engaging the outer edge of said boss.

The numeral 26 indicates a locking-ring which is provided on its periphery at opposite sides, respectively, with an integral lug 15 27 having a cam-surface, or inclined face 28, adapted to engage behind the shoulder 22 of the ears 20, the inner face of the shoulder 22 being inclined to correspond with the incline of the surface 28. The locking-ring 26 20 is also provided with a recess 29 to enable it to pass over a boss 29^a on the nipple, the purpose of which will presently appear. In securing the nipple 19 in position on the coupling-head, the straight portion 24 is inserted 25 in the aperture of the boss 18, the ring 26 is inserted over the nipple and moved into the recess 21, the recess 29 passing over the boss 29^a, and the rear face of said ring engaging the annular shoulder 25 30 of the nipple; the ring is then turned so that the cam-surfaces 28 engage the inner face of the shoulders 22 and force the annular shoulder 25 into firm engagement with the outer face of the boss 18, and by the 35 frictional engagement of the lugs 27 with the shoulders 22 will lock the nipple in such position. In order to prevent the ring 26 from working loose I provide on the cam-face of one of the lugs 27 a series of teeth 40 30 and secure on the outer end of one of the ears 20 a leaf-spring 31, the free end of which is adapted to engage with said teeth and thus prevent the ring from accidentally turning loose. To remove the nipple it is 45 only necessary to lift the spring 31 out of engagement with the teeth 30 and to give one or the other of the lugs 27 a slight blow to loosen the engagement of said lugs with the shoulders 22 when the ring 26 and the 50 nipple 19 can be removed. The rear end of the nipple 19 is provided with an annular recess, and in this recess is fitted a white-metal, lead, or other soft-metal, gasket 32. Mounted in the apertured boss 18 is a contact-member 33 having a rounded head 34 55 adapted to fit against the gasket 32. The head 34 is provided with an annular shoulder 35 which is opposed to a similar shoulder 36 provided at the base of the aperture 60 of the boss 18. A space 37 is normally provided between the shoulders. The outer face 38 of the contact-member 33 projects slightly beyond the outer face of the coupling-head, as more clearly illustrated in 65 Fig. 9; so that when the two coupling-

heads are brought together the corresponding faces 38 of the corresponding contact-members 36 will engage each other and form a steam-tight joint. In the coupling operation the space 37 permits of a slight 70 play of the contact-member 33 in the event that the faces 38 of the opposing contact-members do not engage uniformly at all points, which frequently occurs when the 75 cars are coupled on a curve. The shoulder 75 36 of course prevents the contact-member 33 from falling out of the coupling-head. When opposing coupling-heads are brought together the corresponding contact-members 33 are forced with great pressure against 80 their respective gaskets 32, and these being of soft metal, permit of a firm steam-tight joint being maintained between the contact-members and the inner end of each nipple.

In the case of the nipples 15 and 17, 85 which are for connecting the air-pipes, in place of the soft-metal gaskets used with the steam-pipe above described, I use rubber gaskets 64, which project beyond the meeting faces of the respective coupling-heads and are brought into pressure contact to provide air-tight joints when the 90 couplers are connected, as will be understood. The locking-rings 64^a are the same in construction as that used with the nipple 19, 95 except that they do not have to be provided with the recess 29.

The plunger 5 is slidably mounted in the bracket 7 and is provided on opposite sides with corresponding slots 39 through which 100 extends a hollow pin 40 which is mounted in the bracket 7. Projecting rearwardly from the center of each coupling-head is a hollow arm 41 having opposite flat, parallel faces at its top and bottom the outer end of 105 this arm being inserted and pivotally mounted in the inner end of the plunger 5 through the medium of a hollow pin 42 passing through suitable apertures in the plunger and in the arm 41. Shoulders 43 are provided on the arm 41 to limit its turning movement by contact with the side walls of the plunger. The numeral 44 indicates a bracket which is secured at one end to the 110 side of the arm 41 and at its outer end to the outer side wall of the projection 12. Pivotally mounted at 45 in this bracket is a bell-crank lever 46 having a long arm 47 and a short arm 48. Slidably mounted in the outer wall of the projection 12 is a locking-member 49 having a stem 50 slidably engaging in the side wall of the arm 41. Surrounding the stem 50 and interposed between the side wall of the arm 41 and the inner end of the locking-member 49 is a 115 coil spring 51 which tends normally to force the locking-member 49 outward. When the coupling-heads are in engagement this locking-member will thus engage behind the rim 52 of the opposing 120 125 130 135 140 145 150

coupling-head, which rim surrounds the opening 13 before referred to. Mounted at one end in the hollow pin 40 is a rod 53 having nuts 54 applied to its end to prevent it from being pulled through the pin. The opposite end of the rod 53 is adapted to work through openings in the hollow pin 42 and has connected to it one end of a chain 55, the opposite end of which is connected 10 to the outer end of the arm 47 of the bell-crank lever 46. The free end of the short arm 48 of said lever is located within a recess 56 provided in the locking-member 49, and engages the inner wall of said recess. 15 Mounted within the plunger 5 and surrounding the rod 53 is a coil spring 57 having one end supported on a shouldered sleeve 58 which engages the pin 40, and its other end on a similar sleeve 59, which is held by 20 the spring 57 in engagement with the inner end of the arm 41.

With the cars in the uncoupled relation it will be seen that, with the construction described, the spring 57 will force the plunger 5 outward, thereby moving the coupling-head 3 and the bell-crank lever 46 away from the inner end of the rod 53, and the pull of the arm 47 on the chain 55 will first draw said chain taut and then cause the arm 30 47 to be swung on its pivot 45, which operation moves the arm 48 inward and forces the locking member 49 also to move inward until its outer end is substantially flush with the outer side of the locking-member 35 12. The respective meeting faces of the coupling-heads 3, 4, normally extend beyond the corresponding faces of the car-couplings 1 and 2. When the two cars are coupled, therefore, the coupling-heads 3, 40 and 4 first come into engagement, and the plungers 5, 6, are forced rearwardly in their respective brackets 7 in the continued meeting movement of the cars to permit them to couple. As each coupling-head with its 45 plunger is thus moved rearwardly its spring 57 is compressed, and the inner end of the arm 47 is brought nearer to the outer end of the rod 53. This acts to release the arm 47 by slackening the chain 55 and permits the spring 51 to throw the locking-member 49 outward to engage over the rim 52, such position of the parts being more clearly illustrated in Fig. 2. The springs 51 and 57 are substantially of the same 55 strength, but the spring 57 is enabled to overcome the power of the spring 51 by reason of the greater leverage afforded by the length of the arm 47. An important feature of this construction is the fact that the 60 locking-member 49 moves in right lines in a horizontal plane and its movement is thus accomplished with the minimum amount of frictional resistance; and this construction also provides the highest measure of security as to its locking function, as it is

practically impossible for any movement between the coupling-heads to tend to force the locking-member 49 inward, the pull thereon being necessarily at right angles to its line of movement.

The engagement of the inner end of the arm 41 with the sleeve 59 provides for automatically adjusting the arm 41 to normal position after its displacement. That is to say, if the arm 41 be turned about the pivot 42 to one side, the sleeve 59 will yield on that side against the resistance of the spring 57. As soon as the pressure which distorted the position of the arm 41 is removed the spring 57 will at once operate to restore 80 the parts to normal position.

In order to provide for the escape of condensed steam from the nipple 19 and the pipe connected therewith, I provide an aperture 60 in the bottom of the nipple 19, and 85 a screw-threaded aperture in alignment therewith in the boss 29^a on the top of the nipple. Co-operating with the aperture 60 is a zinc, or other, plug 61 having a screw-threaded head 62 securely sealed in said 90 screw-threaded aperture. The lower end of the plug 61 is tapered to correspond with tapered walls of the opening 60, and when the couplers are in use the heat of the steam causes the plug 61 to expand and close 95 the aperture 60. When the coupling heads are uncoupled, or when no steam is passing through the steam-pipe, the nipple 19 will cool off and the plug 61 will accordingly contract and open the aperture 60 and permit water of condensation to drip through the same.

The numerals 63 indicate electrical contact plugs, but these, with their connections, form no part of the present invention.

The numeral 65 indicates a cup mounted on the bracket 7 in which is mounted an adjustable spring-controlled support 66 for the plunger 5 and its coupling-head, the construction in this regard being substantially 105 the same as shown in my application above referred to. It may be stated, however, that in the present case I prefer to form the bracket 7 and cup 65 in two parts, which are connected together by bolts or the like, 110 indicated generally by 67, as well as by the bolts 9 which pass from side to side of the bracket.

I claim:

1. In a train-pipe coupling, a bracket, a hollow plunger mounted therein provided with slots in its opposite walls, a pin mounted in said bracket and passing through said slots, a coupling-head pivotally mounted on said plunger, a coil spring located in said plunger and interposed between said coupling-head and said pin, a spring-controlled locking-member slidably mounted in said coupling-head and movable outwardly beyond the surface thereof, and means opera- 120 125 130

- tively connecting said locking-member and said pin and adapted normally to hold the locking-member in a retracted position under the action of said interposed spring.
5. 2. In a train-pipe coupling, a bracket, a plunger slidably mounted therein carrying a coupling-head, a spring interposed between the bracket and the coupling-head and tending normally to force the plunger and coupling-head outward, a locking-member slidably mounted in said coupling-head, a bell-crank lever pivotally mounted on the coupling-head for actuating said locking-member, a rod mounted on said bracket and 10 extending through said plunger, and a chain connecting the free end of said rod and one end of said bell-crank lever.
3. In a train-pipe coupling, a bracket, a plunger slidably mounted therein, a coupling-head, a pin pivotally connecting said coupling-head and plunger, a spring located within the plunger and interposed between the coupling-head and said bracket, a rod mounted on the bracket and extending 15 longitudinally through said plunger and adapted to work through an opening in said
- pin, a spring-controlled locking member slidably mounted in said coupling-head, a bell-crank lever pivotally mounted on said coupling-head for actuating said locking-member, and a chain connecting said rod and one arm of said bell-crank lever. 30
4. In a train-pipe coupling, a bracket, a plunger mounted therein, a coupling-head pivotally mounted on said plunger, a spring interposed between said bracket and said coupling-head, a spring-controlled locking-member slidably mounted in said coupling-head to move in right lines at right angles to the line of draft, and means operatively 35 connecting said locking-member with said bracket for normally holding said locking-member retracted under the action of said interposed spring and against the resistance of the spring of the locking-member. 40
- In testimony whereof, I have hereunto set my hand in presence of two subscribing witnesses.

VOTAW S. DURBIN.
